UNITED STATES PATENT OFFICE.

WILLIAM JACKSON, OF BROOKLYN, NEW YORK.

PRINTING MACHINE FOR WALL PAPER.

Application filed January 25, 1926. Serial No. 83,677.

This invention relates to an improvement in machines for manufacturing wall paper.

An object of the invention is to provide a construction of machine which will permit 5 the printing of a greater number of colors or designs than has hitherto been possible.

A further object resides in the provision of means whereby the machine can not only print one or more extra colors, but can in- 10 one operation perform a cutting operation especially when wall paper borders are being run through the machine.

A still further object resides in the provision of means whereby a printing roller 15 and a cutting roller may be substituted readily for each other without disturbing the other parts of the apparatus.

The invention is illustrated in the drawings, of which—

20 Figure 1 is a side elevation of the machine;

Figure 2 is an enlarged end elevation with a portion broken away showing the means for printing an extra color;

25 Figure 3 is a section taken through the apparatus shown in Figure 2;

Figure 4 is an elevation showing the means for cutting the wall paper into borders.

30 The form of the invention shown in the drawings is a preferred form, although it is understood that modifications in the construction and arrangement of the parts and in the character of the materials used may 35 be adopted without departing from the spirit of the invention as set forth in the appended claim.

In its general aspect the invention in- 40 cludes the addition to a standard wall paper making machine an apparatus which will permit more than the usual number of colors to be placed on the wall paper during the continuous operation of the machine and which will at the same time permit the 45 paper to be cut in borders while being printed.

In the standard wall paper making ma- 50 chine the paper is fed through the machine over the periphery of a large drum around a portion of the periphery of which a series 55 of printing rollers are disposed, and as the paper is passed around the drum each roller applies its design to the paper. The drum is ordinarily mounted in a frame and the printing rollers are preferably disposed around the drum to cover slightly less than

half its periphery, so that the drum can be lifted out of the frame when desired, especially if the printing rollers have to be repaired or otherwise attended to. By reason of the fact, therefore, that the printing cannot occupy more than half the periphery of the drum the standard machines have only been able to print a design in twelve colors. By reason of my invention, however, I can print at least thirteen colors and it is possible to print more, and in some cases it is also possible to print thirteen colors and at the same time cut a border in the one operation of running the paper through the machine.

To achieve this object I preferably mount an additional printing roller in the path of the paper before it reaches the drum. As a matter of fact, of course, I can dispose an indefinite number of additional printing rollers in the line of the paper before it reaches the drum. Furthermore, after the paper has left the drum I may pass it through additional rollers which can either print or cut it. These auxiliary rollers are removably mounted on a frame so that they can be easily withdrawn therefrom for the purpose of replacing a roller. This is especially convenient with respect to the rollers disposed in the line of the paper after it leaves the drum, because in this position the rollers can be removed, so that for instance a printing roller may be substituted for a cutting roller, or vice versa.

In the preferred form of the invention shown in the drawings, Figure 1 shows a frame 10 having a vertical slot 11 in the bottom of which a shaft 12 is disposed. This shaft supports a drum 13 which has at each end of its periphery gears 14. These gears mesh with a plurality of gears such as 15 mounted on suitable shafts such as 16 supporting the usual printing rollers. It will be noted that there are twelve of these printing rollers such as 17 mounted around the lower half of the drum and with each roller is associated a color-applying belt 18 dipping into a color trough 19. The paper 20 is passed through the machine between the drum 13 and the various rollers 17 and each roller applies its design in the proper color to the paper in the usual manner. The movement of the paper is indicated by the arrows disposed thereon, and at the right of the machine in Figure 1, I dispose an auxiliary frame 21 on which is mounted three gears 22,

23 and 24, meshing with each other, the gear 22 engaging one of the gears 14 and the gear 23 mounted on a shaft and acting as an idler. An additional gear 22^a is arranged 45 adjacent gear 22, said additional gear 22^a meshing with gear 14 and gear 28. The gear 24 is mounted on a shaft supporting a printing or cutting roller 25 (see Figure 3). This printing or cutting roller 25 bears 50 10 against a pressure roller 26 suitably mounted in the frame. Engaging with the gear 22^a is a large gear 28 which in turn meshes with a gear 29 mounted on a shaft 30 supporting a belt roller 31. A color applying belt 32 55 15 passes over this roller and at the other end connects with a color roller 33 mounted in a color trough 34.

As shown in Figure 2 the roller 31, the 60 20 printing or cutting roller 25 and the tension roller 35 are mounted on shafts, the ends of which are connected to slideable frame members 36 and 37 having tongues 38 engaging with suitable grooves in the main frame so that these three rollers can be drawn out 65 25 away from the paper 20 and a new set of rollers can be substituted quickly. In other words the printing roller and associated rollers shown in Figure 3 can be readily withdrawn and an identical set of rollers can be 70 30 substituted therefor, except a cutting roller is provided instead of printing roller 25, so that the paper may be cut or printed at will and this change can be effected with a minimum expenditure of time and labor. As 75 35 shown in Figure 1, at the left of the machine before the paper moves on to the drum a set of apparatus is furnished in every way similar to the apparatus shown at the right of the drum in Figure 1.

40 In the operation of the machine the auxiliary apparatus at the left of the drum is

generally employed to print an extra color or design such as is indicated by the numeral 39 in Figure 2, and the auxiliary apparatus at the right of the drum in Figure 1 is generally employed to cut the paper, as shown in Figure 4, wherein the roller 25 is used as a cutting roller especially when bordered paper is being manufactured.

45 It is therefore possible with this machine 50 to print two additional colors or to print one additional color and at the same time cut the paper after it leaves the drum. This additional operation is effected without eliminating the possibility of lifting the 55 main drum out of the frame when desired.

What I claim is:

In a wall paper making machine a frame formed with a vertical slot, a drum having a shaft fitted into said slot whereby the drum 60 may be bodily moved out of the frame at any time, a plurality of printing rollers disposed around the periphery of the drum between which and the drum the paper to be printed is adapted to be passed, said printing 65 rollers being carried by the frame below the center of the drum when the drum is in functioning position, auxiliary means above the center of the drum spaced radially therefrom a sufficient distance to allow the drum to 70 pass when moved bodily out of the frame, said auxiliary means being disposed in the path of the paper before it reaches the drum for printing additional colors and designs thereon, and auxiliary means in the path of 75 the paper after it leaves the drum for cutting the paper longitudinally, said auxiliary means being spaced sufficiently from the drum to permit the drum to be removed from said frame.

WILLIAM JACKSON.
